W.B. Bennett,

Portable Fence,

No 17,075.

Patented Apr 21, 1854.

UNITED STATES PATENT OFFICE.

WM. B. BURNETT, OF LYONS, NEW YORK.

METHOD OF CLAMPING AND UNCLAMPING PANELS OF PORTABLE FIELD-FENCES.

Specification of Letters Patent No. 17,075, dated April 21, 1857.

To all whom it may concern:

Be it known that I, WM. B. BURNETT, of Lyons, in Wayne county and State of New York, have invented a new and useful Improvement in Portable Fences, and do hereby declare that the following is a full, clear, and exact description thereof, reference being had to the accompanying drawing through letters of reference marked thereon,

10 in which—

Figure 1, represents, in part, a top view of the fence, and in part, a horizontal section, taken below the two upper rails. Fig. 2, represents a perspective view. Fig. 3, a 15 side view of the connecting link.

The same letters of reference appearing in the several figures, indicate like parts.

The nature of my invention, consists in an improvement in the connecting link of my 20 "portable fence" patented Dec., 1856, whereby a gate may be opened in any portion of the fence, or any portion of it may be taken down and removed, without commencing at the part set up first, or last, as 25 was necessary with my original fence, and which is very desirable, for evident reasons unnecessary to mention here.

To enable others to make and use my fence as improved, I will describe its construction.

30 The trays (A) are composed of three rails (B), and two or more uprights (C); and as many additional rails as required, which may be either of wood or iron. The rails (B) are all of uniform length, and are 35 arranged so as to project alternately at either end of the tray, so that when set up, in a zigzag line, the short ends of the rails of one tray, will abut diagonally against the long ends of the rails of the other, and

thus support each other in a vertical position; they are then secured together endwise by a clamp (D), which hooks onto the end uprights of the two trays, across the inner side of the angle formed by them; this clamp is constructed with a hook (u) at one end, 40 and at the other with a turn button (e), which, when in place, is secured by a pin (i), inserted diagonally in a hole (o), which is formed half in the body of the clamp, and half in the button, which prevents it from 45 turning, and forms a hook at that end also; this clamp can be put on or taken off, without changing the position of the trays, by 50 withdrawing the pin (i) and turning the button, so that an opening may be made in 55 any part of the fence. These button clamps may be made of wood or metal, and may be used throughout the fence, or only at given points where gates might be required, solid 60 clamps being used at all other portions. In 65 all other particulars, my fence is the same as that previously referred to, as patented by me in December 1856, any further description therefore, would be unnecessary at this time.

Having thus described my improvement, what I claim as new and desire to secure by Letters Patent; is—

The turn-button clamp, or its equivalent, for connecting the trays of a portable fence, 70 constructed, arranged and operating, in the manner substantially as set forth.

In testimony whereof I hereunto set my hand.

WM. B. BURNETT.
